United States Patent

Des. 238,052
Patented Dec. 16, 1975

238,052

CABINET COVER

Charles C. Boris, 228 Glen Oaks Ave.,
Temple Terrace, Fla. 33617

Filed Dec. 8, 1972, Ser. No. 313,401

Term of patent 14 years

Int. Cl. D9—99

U.S. Cl. D9—259

FIG. 1

FIG. 3

FIG. 1 is a front perspective view of a cabinet cover showing my new design.

FIG. 2 is a similar view with the front panel in open position.

FIG. 3 is a rear perspective view on a reduced scale.

The broken line showing of a cabinet and carrying handle are for illustrative purposes only. The remaining broken lines represent stitching.

I claim:

The ornamental design for a cabinet cover, as shown and described.
